UNITED STATES PATENT OFFICE

167,514

COMBINATION CONTOUR CHAIR AND OTTOMAN OR SIMILAR ARTICLE

Edward Russell Hicks, West Los Angeles, Calif.

Application July 9, 1951, Serial No. 15,798

Term of patent 14 years

(Cl. D15—11)

To all whom it may concern:

Be it known that I, Edward Russell Hicks, a citizen of the United States, residing in the city of West Los Angeles, in the county of Los Angeles, and State of California, have invented a new, original, and ornamental Design for a Combination Contour Chair and Ottoman or Similar Article, of which the following is a specification, reference being had to the accompanying drawing, forming a part thereof.

Figure 1 is a perspective view of a combination contour chair and ottoman or similar article, showing my new design folded and in position for use as an ottoman.

Figure 2 is a similar view showing the same in open condition and the back rest elevated.

Figure 3 is a view similar to Figure 2 showing the back rest portion in partially elevated posi-

tion and the leg rest portion in elevated position.

Figure 4 is a perspective view of the same shown in partially open position.

I claim:

The ornamental design for a combination contour chair and ottoman or similar article, as shown.

EDWARD RUSSELL HICKS.
